CLAIM

The ornamental design for a camping table, as shown and described.

DESCRIPTION

FIG. 1 is a top perspective view of a camping table showing my design;

FIG. 2 is bottom perspective view;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The dashed or broken lines shown in the drawings depict portions of the camping table in which the design is embodied that form no part of the claimed design.
